UNITED STATES PATENT OFFICE.

CHARLES W. MUELLER, OF ST. LOUIS, MISSOURI, ASSIGNOR TO LEWIS INVISIBLE STITCH MACHINE CO., A CORPORATION OF MAINE.

QUICK-ADJUSTING PLUNGER MECHANISM FOR BLINDSTITCH SEWING MACHINES.

Application filed January 7, 1924. Serial No. 684,745.

To all whom it may concern:

Be it known that CHARLES W. MUELLER, a citizen of the United States, residing at St. Louis, State of Missouri, has invented certain new and useful Improvements in Quick-Adjusting Plunger Mechanism for Blindstitch Sewing Machines, of which the following is a specification.

This invention relates to new and useful improvements in blind stitch sewing machines generally, although more particularly to the plunger mechanism thereof.

In blind stitch operations it is very often desirable to vary the depth of the needle penetration, such as, when stitching over pockets, when going from one weight of fabric to another, or when going from an unironed fabric to an ironed fabric. Heretofore, in blind stitch sewing machines such as is shown and described in my copending application Ser. No. 692,696 filed February 14, 1924, the bodily vertical position of reciprocation of the plunger is adjusted through the medium of an endwise movable sleeve which is normally clamped in the frame. It is necessary to first loosen this clamp before adjusting the sleeve in order to effect adjustment of the bodily vertical position of reciprocation of the plunger. This mechanism is therefore slow and tedious and in certain blind stitch operations, in order to obtain maximum production, it is desirable to provide a mechanism whereby the bodily vertical position of reciprocation of the plunger may be quickly adjusted to suit the various working conditions.

It is, therefore, one of the principal objects of my invention to provide an adjusting mechanism of the character described which is capable of being rapidly adjusted without having to first release the clamp from the adjusting sleeve.

Another object of the invention is to provide a plunger adjusting mechanism with means whereby a predetermined adjustment within definite limits may be readily made and whereby the plunger mechanism may be readily returned to its initial position of adjustment.

With the above and other objects in view which will more readily appear as the nature of the invention is better understood, the same consists in the novel construction, combination and arrangement of parts hereinaf-

ter more fully described, illustrated and claimed.

In the accompanying drawings which illustrate one embodiment of my invention:

Figure 1 is a front elevation of a sewing machine constructed in accordance with my invention, the frame of the machine being broken away to better disclose the plunger mechanism..

Figure 2 is a vertical transverse sectional view taken on the line 2—2 of Figure 1 looking towards the left hand end of the machine.

Figure 3 is a detail top plan view of the plunger adjusting mechanism.

Figure 4 is a detail end elevation of the machine.

Figure 5 is an enlarged longitudinal sectional view showing the driving connections between the plunger and the cradle, and

Figure 6 is a detail view of the vertically movable pivot block for the feed mechanism.

Like reference numerals designate corresponding parts in all the figures of the drawings.

The sewing machine consists of a base 5 having at one end the work handling mechanism, a post 6 which extends upwardly from the other end thereof and an overhanging arm 7 which is supported by the post and carries at its outer or free end a stitching head 8, said stitching head being disposed above the work handling mechanism. This stitching head is of the type shown and described in my copending application mentioned above and it is, therefore, thought that a detail description thereof is unnecessary. The stitching head carries at its lower extremity a presser-foot 9 for cooperation with the stitch forming and work-handling mechanisms.

The operating parts carried by the stitching head 8 and the work-handling mechanism carried by the base 5 are driven from a main shaft 10 which extends longitudinally in the overhanging arm 7 and is suitably journaled therein, said shaft having a hand wheel pulley 11 fixed to the right hand end thereof.

The work-handling mechanism which cooperates with the presser foot 9 includes a feed dog 12 and a work clamp 13. The feed dog is of the 4-motion type, that is, it has a backward and forward movement and an

up and down movement. The backward and forward movement of the feed dog is obtained through a rock shaft 14, and the up and down movement of the feed dog is obtained from a rock shaft 15. These rock shafts 14 and 15 extend longitudinally within the base 5 and have their right hand ends journaled in bearings formed in a depending lug 16 and their left hand ends journaled in bearings formed in a block 17 detachably secured to the left hand end of the base 5 by screws 18—18. Fixed to the outer end of the shaft 14 is a rock arm 19 and pivotally connecting the outer end of the rock arm and the forward extremity of the feed dog 12 is a link 20. The rock arm 19 extends in a general vertical direction and the link 20 extends in a general horizontal direction, thus upon movement of the rock arm the link 20 will impart backward and forward movements to the feed dog 12. The feed dog 12 is pivotally connected as at 21 to the upper end of a substantially vertically disposed link 22, the lower end of said link being pivotally connected as at 23 to the horizontal arm 24 of a bell crank lever 25, the vertical arm 26 of said bell crank lever being pivotally connected as at 27 to one end of a link 28, the other end of said link 28 being pivotally connected as at 29 to the outer end of a vertically disposed rock arm 30 fixed to the "feed lift" shaft 15. In order to maintain the feed surface of the feed dog in a substantially horizontal plane during the feeding movements thereof, I provide a spring 31 which is connected between a pin 32 on the link 22 and a pendant tail 33 fixed to the feed dog. It will, therefore, be observed that upon rocking movement of the shaft 15 the vertical link 22 will be bodily raised and lowered and consequently the feed dog will be given its up and down movements. By proper timing of the shafts 14 and 15 a 4-way feed motion will be imparted to the feed dog.

The bell crank lever 25 is pivoted as at 34, and this pivot is fixed to a head 35 secured to the lower end of a guide post 36, said head and post forming a vertically movable carrier. The post 36 is mounted for vertical sliding movements in a bore formed in the block 17, and this block is formed with a seat 37 for receiving and limiting the upward movement of the carrier. This carrier is normally held in its highest position by means of a flat spring 38 the inner end of which is rigidly secured to the base 5 and the free end thereof is disposed under the carrier so as to yieldably hold the latter in its highest position. The upper end of the post projects above the block 17 and carries a pair of rearwardly extending arms 39—39 between which is pivoted as at 40 the work clamp 13. From the foregoing, it will be observed that when the carrier is moved

downwardly against the tension of the spring 38, both the feed dog 12 and the work clamp 13 will be correspondingly moved, thus permitting the work presenting mechanism to be depressed as an entirety. 70 In order to so depress the work presenting mechanism, I have provided an operating lever 41 which is fulcrumed on the base 5 and has one end disposed in contact with the upper face of the head 35. The other end 75 of the lever is adapted to be raised through the application of a knee shifting device or treadle, neither of which however is shown in the drawings.

From the foregoing, it will be observed 80 that when the feed dog is elevated to its highest position, the fulcrum of the bell crank lever 25 is then shifted to the pivot 23 and consequently the last part of the rocking movement of the crank arm 30 will 85 cause the bell crank 25 to be moved downwardly about its fulcrum 23 thus lowering the work clamp 13. The parts are so timed that the work clamp is thus lowered prior to the feeding movement of the feed dog. The 90 reverse order of movement will take place at substantially the time when the feed dog reaches the end of its feeding stroke, thus causing the clamp to engage the fabric and clamp the latter against the foot prior to 95 the time the feed dog begins its downward movement.

In order to rock the shaft 14 and the shaft 15 I provide the main shaft 10 with eccentrics 42 and 43 respectively. A connection rod 44 has its upper end engageable with the eccentric 42 and its lower end pivotally connected as at 45 to a rock arm 46 fixed to the rock shaft 14. A connection rod 47 has its upper end engageable with the eccentric 43 100 and its lower end pivotally connected as at 48 to a rock arm 49 fixed to the shaft 15. It will be noted that the connection rods 44 and 47 are disposed within the post 6 of the machine frame. 105

The fabric as it is fed past the stitching head is adapted to be intermittently crimped or bent so as to form a node which will be positioned in the path of the needle whereby the latter will, or will not, depending upon the height of the node, enter said node and project a penetrant needle thread loop there-through, as will hereinafter be more fully described. In order to provide for this crimping or bending action of the material, the presser foot 9 is formed with an opening 50. The material is upwardly bent or crimped into this opening by means of a reciprocatory plunger 51 which extends upwardly through the feed dog 12 and work clamp 13. This plunger is mounted for vertical sliding movements within a barrel 52 fitted within a bore 53 formed in the end block 17. The lower end of the plunger 51 is formed with a reduced end 54 forming a 110 115 120 125 130

resultant shoulder 55. The lower end of the barrel 52 is fixed to a lug 56 and the reduced end 54 of the plunger extends freely through an opening 57 formed in said lug and 5 threaded onto the lower projecting end thereof are lock nuts 58. Disposed within the barrel 52 between the shoulder 55 of the plunger and the lug 56 is a coil spring 59 which yieldably holds the plunger in its 10 highest position relative to the lug 56. It will be evident that when the barrel is moved upwardly the plunger will be moved therewith, but just as soon as the plunger engages the fabric a resistance to the upward movement of said plunger will take place and the spring 59 will permit the barrel to continue its movement while the plunger spring 59 is being compressed.

The plunger 51 is vertically reciprocated 20 through the medium of a rock shaft 60 which extends longitudinally of the base 5. The rock shaft 60 is provided with a crank arm 61 which is connected by a link 62 to the lug 56. The rock shaft 60 is located 25 below the plunger and the link 62 extends substantially vertically when the plunger is at its highest position.

For the purpose of bodily varying the vertical position of reciprocation of the 30 plunger, I have supported the rock shaft 60 for vertical bodily movements and have journaled the shaft in bearings formed in a cradle or rocking frame which I have designated as a whole by the reference numeral 35 63. This cradle includes a rock shaft 64 having one end supported for rocking movements on pins 65—65 respectively carried by the end wall of the base 5 and the depending lug 16 of said base. The rock 40 shaft 64 is provided with downwardly and rearwardly extending rock arms 66—66 in which the plunger rock shaft 60 is journaled. The rock shaft 64 of the cradle is provided adjacent its right end with a laterally and longitudinally extending rock arm 67 having forwardly extending arms 68—68. Disposed between the arms 68—68 is a sleeve 69 forming a slide bearing for the lower end 45 of a vertically disposed cam roller shaft 70. The sleeve 69 is supported on the arms 68—68 by horizontally disposed pivot pins 71—71. Fixed to the sleeve 69 is a face cam 72 and this cam is formed on its upper face with a curved surface containing diametrically 50 opposed high points 73—73 and diametrically opposed low points 74—74. The cam roller shaft 70 extends upwardly through the post 6 of the frame and is driven from the main shaft 10 by a gear coupling 75 55 which reduces the speed of rotation of the cam roller shaft 70 relative to the main shaft 10 by the ratio 1 to 4. This gear coupling 75 includes a spiral gear 75^a which is fixed to the cam roller shaft 70 through the medium 60 of a collar 75^b and a spiral gear 75^c which is

fixed to the main shaft 10. The cam roller shaft extends through a concentric opening in the cam 72 and fixed to the shaft directly above the cam face of said cam is a sleeve 76 which carries a cam roller 77 engageable 70 with the cam face of the cam. The upper end of the cam roller shaft 70 above the gear coupling 75 is mounted within a sleeve 78 which has threaded engagement with an opening formed in a plate 79 which is detachably secured to the upper end of the frame. The lower end of the sleeve rests on the collar 75^b of the gear coupling. Fixed to the upper end of the sleeve 78 is a laterally extending hand lever 80 by 80 means of which the sleeve may be turned and the vertical position thereof consequently adjusted. A screw 70^a is threaded into the upper end of the cam roller shaft 70 and the head of this screw bears against the 85 upper end of the sleeve 78. Thus, the cam roller shaft 70 is held against longitudinal movement relative to the sleeve 78 by means of the gear collar 75^b and the screw 70^a.

The plunger shaft 60 is rocked in the supporting cradle or frame 63 by the rock arm 49, the outer end of which is pivotally connected as at 49^a, the lower end of the link being pivotally connected as at 49^c to a rock arm 60^c fixed to the plunger shaft 60. Inasmuch as the cam 72 is provided with two high points and two low points, and the main shaft makes four complete revolutions to one of the cam roller shaft 70, it follows that the bodily position of reciprocation of 100 the plunger will be elevated during every other revolution of the main shaft.

By turning the hand lever 80 in a clockwise direction, the sleeve 78 will be moved downwardly, and through the medium of 105 the gear collar 75^b the cam roller shaft 70 will be moved downwardly for a corresponding distance. This downward movement of the cam roller shaft through the medium of the roller 77 causes the cradle 63 to be rocked, thus elevating the plunger shaft 60, the latter being moved upwardly in an arc about the pivot of the cradle. The upward bodily movement of the shaft 60 will in turn bodily elevate the position of 110 reciprocation of the plunger 51 through the medium of the rock arm 61, link 62 and lug 56.

By turning the hand lever 80 in an anti-clockwise direction, the cam roller shaft 70 will be elevated and the plunger rock shaft 60 will be lowered, thus lowering the bodily 115 position of reciprocation of the plunger 51.

In order to lock the sleeve 78 in a predetermined position of adjustment, and yet permit of a rapid release and new adjustment, I have provided the hand lever 80 with a releasable latch which cooperates with the plate 79. This latch comprises an upwardly extending housing 81 which is 120 125 130

- fixed to and is located at the outer end of the hand lever 80. This housing has a closed upper end and an open lower end. Disposed within the housing is a vertically 5 movable latch-pin 82, the upper end thereof projecting through an opening formed in the upper end of the housing and having a finger piece or head 83 fixed thereon, the lower end of said latch-pin projecting below 10 said housing for engagement in any one of a plurality of seats 84 which are formed in the plate 79. These seats are spaced apart and are disposed in a circle which is concentric to the sleeve 78. Fixed to the 15 lower portion of the latch-pin 82 is a shoulder 85, and disposed around the pin between the upper end of the housing and said shoulder is a coil spring 86 which normally urges the latch-pin downwardly.
- 20 Thus, after the plunger mechanism has been set, and the operator desires to effect a quick adjustment of the plunger, either up or down, it is only necessary to raise the latch-pin against the tension of the spring 25 86 and then while holding the latch-pin in its raised position, swing the hand lever 80 in the desired direction for required distance, and then release the pin whereupon the latter will automatically seat itself in 30 the registering seat 84. The operator, by counting the number of seats intervening between the seat of original setting and the seat of adjustment, may readily return the parts to their original setting.
- 35 A quick adjustment of the plunger mechanism is often desired, such as during the operation of felling the facings to coats in order to avoid sewing down the inside pockets. In this operation, it is necessary to 40 lower the bodily position of reciprocation of the plunger so as to insure the needle penetrating only the upper ply of material, or when going from an unironed garment to an ironed garment it is necessary to raise 45 the bodily position of reciprocation of the plunger in order for the needle to penetrate said unironed garment, or when going from a garment of one weight to a garment of another weight.
- 50 I claim:
1. In a blind-stitch sewing machine, the combination with a presser-foot, of a vertically reciprocatory plunger therebelow, a main shaft, means connected with said shaft 55 for reciprocating said plunger, and means for quickly adjusting the vertical bodily position of reciprocation of said plunger, said adjusting means including an endwise movable cam roller shaft, means for rotating 60 said cam roller shaft from said main shaft, and means connected to said cam roller shaft including a lever-handle for moving the cam roller shaft endwise to adjust the vertical bodily position of reciprocation of 65 said plunger.
  2. In a blind-stitch sewing machine, the combination with a presser-foot, of a vertically reciprocatory plunger therebelow, a main shaft, means connected with said shaft for reciprocating said plunger, and means 70 for quickly adjusting the vertical bodily position of reciprocation of said plunger, said adjusting means including a rocking-frame, a cam carried by said frame, an endwise movable cam roller shaft, a roller on said shaft cooperating with said cam for oscillating said frame, means for rotating said cam roller shaft from said main shaft, and means connected to said cam roller shaft including a lever-handle for moving the cam roller shaft endwise to adjust the vertical bodily position of reciprocation of 75 said plunger.
  3. In a blind-stitch sewing machine, the combination with a main frame, of a presser-foot connected thereto, a vertically reciprocatory plunger therebelow, means for reciprocating said plunger, and means for quickly adjusting the vertical bodily position of reciprocation of said plunger including an 80 endwise movable cam roller shaft, a sleeve surrounding said cam roller shaft and having threaded engagement with said main frame, said sleeve engaging the shaft to move the shaft endwise upon rotation of 85 the sleeve, and a lever arm fixed to the sleeve for rotating the latter.
  4. In a blind-stitch sewing machine, the combination with a main frame, of a presser-foot connected thereto, a vertically reciprocatory plunger therebelow, means for reciprocating said plunger, and means for quickly adjusting the vertical bodily position of reciprocation of said plunger including an endwise movable cam roller 90 shaft, a sleeve surrounding said cam roller shaft and having threaded engagement with said main frame, said sleeve engaging the shaft to move the shaft endwise upon rotation of 95 the sleeve, and a lever arm fixed to the sleeve for rotating the latter.
  5. In a blind-stitch sewing machine, the combination with a main frame, of a presser-foot connected thereto, a vertically reciprocatory plunger therebelow, means for reciprocating said plunger, and means for quickly adjusting the vertical bodily position of reciprocation of said plunger including an endwise movable cam roller shaft, a sleeve surrounding said cam roller shaft and having threaded engagement with said main frame, said sleeve engaging the shaft to 100 move the shaft endwise upon rotation of 105 the sleeve, a lever arm fixed to the sleeve for rotating the latter, and cooperating means between the lever-handle and the main frame to lock the former in a predetermined position of adjustment.
  6. In a blind-stitch sewing machine, the combination with a main frame, of a presser-foot connected thereto, a vertically reciprocatory plunger therebelow, means for reciprocating said plunger, and means for quickly adjusting the vertical bodily position of reciprocation of said plunger including an endwise movable cam roller shaft, a sleeve surrounding said cam roller shaft and having threaded engagement with said main frame, said sleeve engaging the shaft to 110 move the shaft endwise upon rotation of 115 the sleeve, a lever-handle for quickly rotating the sleeve, said frame being provided with a plurality of spaced seats arranged in concentric line about the sleeve, and readily re- 120 125 130

leasable means carried by the lever-handle for engagement with any one of said seats.

6. In a blind-stitch sewing machine, the combination with a main frame, of a presser-foot connected thereto, a vertically reciprocating plunger therebelow, means for reciprocating said plunger, and means for quickly adjusting the vertical bodily position of reciprocation of said plunger including an endwise movable cam roller shaft, a sleeve surrounding said cam roller shaft and having threaded engagement with said main frame, said sleeve engaging the shaft to move the shaft endwise upon rotation of the sleeve, a lever-handle for quickly rotating the sleeve, said frame being provided with a plurality of spaced seats arranged in a concentric line about the sleeve, and a spring actuated latch carried by the lever handle for engagement with any one of said seats.

7. In a blind-stitch sewing machine, the combination with a main frame, of a presser-foot connected thereto, a vertically reciprocating plunger therebelow, means for reciprocating said plunger, and means for

quickly adjusting the vertical bodily position of reciprocation of said plunger including an endwise movable cam roller shaft, a sleeve surrounding said cam roller shaft and having threaded engagement with said main frame, said sleeve engaging the shaft to move the shaft endwise upon rotation of the sleeve, a lever-handle for quickly rotating the sleeve, said frame being provided with a plurality of spaced seats arranged in a concentric line about the sleeve, a vertically movable latch mounted in said lever-handle and engageable with any one of said seats, a spring carried by said lever-handle for normally urging said latch downwardly into engagement with a predetermined seat, and a head carried by said latch for elevating the latter from engagement with the predetermined seat.

In testimony whereof I hereunto affix my signature in the presence of two witnesses.

CHARLES W. MUELLER.
